TRACK ELEMENT FOR ENDLESS TRACKS

Dominic Plastino, Montreal, Quebec, Canada, assignor to
ANFA Tractor Parts Ltd., Montreal, Quebec, Canada

Filed Jan. 21, 1971, Ser. No. 108,669

Claims priority, application Canada Oct. 15, 1970

Term of patent 14 years

Int. Cl. D15—04

U.S. Cl. D40—5

FIG. 2

FIG. 3

FIG. 4

FIG. 5

FIG. 6

FIG. 1 is a top plan view of a track element for endless tracks, showing my new design;

FIG. 2 is a side elevational view;

FIG. 3 is an end view taken from the plane of the line 3-3 in FIG. 1;

FIG. 4 is a sectional view taken in the plane of the line 4-4 in FIG. 1;

FIG. 5 is a sectional view taken in the plane of the line 5-5 in FIG. 1;

FIG. 6 is a sectional view taken in the plane of the line 6-6 in FIG. 1;

FIG. 7 is a bottom plan view; and

FIG. 8 is a sectional view taken in the plane of the line 8-8 in FIG. 7.

I claim:
The ornamental design for a track element for endless tracks, as shown.
